UNITED STATES PATENT OFFICE.

HARRY JAY THOMPSON, OF SAN FRANCISCO, CALIFORNIA, ASSIGNOR TO NATIONAL FIBREFORM COMPANY, OF SAN FRANCISCO, CALIFORNIA.

FRUIT CARRIER.

Application filed August 2, 1921. Serial No. 489,249.

To all whom it may concern:

Be it known that I, HARRY J. THOMPSON, a citizen of the United States, residing at San Francisco, in the county of San Francisco and State of California, have invented a new and useful Fruit Carrier, of which the following is a specification.

This invention relates to carriers designed for holding fruits such as apples while being transported from place to place, one of the objects being to provide molded crate fillers or mats formed of paper pulp or a like material suitably medicated whereby the fruit is not only protected from contact with each other and from handing but is also protected against the action of germs and the resultant decay caused by bruising.

Another object is to provide mats or fillers which can be compactly nested while in use so that the fruit when held within the containers will require but slightly more space than fruit packed in the usual way.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

35 In said drawings

Figure 1 is a plan view of a stack of mats or fillers assembled in nested relation to form a container.

40 Figure 2 is a section on line 2-2, Figure 1.

Figure 3 is a section on line 3-3, Figure 1.

Figure 4 is a plan view showing the recessed face of one of the mats or fillers.

45 Figure 5 is a plan view showing the back of said mat or filler.

Figure 6 is a plan view showing the recessed face of another mat or filler.

50 Figure 7 is a plan view of the back face thereof.

The container constituting this invention is made up of the two kinds of mats or fillers each of which comprises a sheet of paper pulp or the like molded to proper form and proportions. One of the mats, which has

been illustrated in Figures 4 and 5, consists of a flat sheet 1 having rows of recesses 2 molded therein, the recesses of each row communicating through reduced passages 3 and each recess being of a size suitable to hold an apple or other fruit of the particular grade to be packed. In the present instance the sheet 1 has four recesses in each series and, obviously, the same number of projections or protuberances are provided on the back face of the sheet as shown at 4 in Figure 5. The other form of mat used in the container is formed of the same kind of material and comprises a flat sheet 5 having series of depressions 6 so shaped and proportioned as to properly hold fruit to be packed. These series of depressions result in the formation of corresponding projections or protuberances 7 on the back of the sheet, the same being so located that when the back of one sheet 5 is placed on the back of one of the sheets 1 the protuberances 7 will nest between the protuberances 2 as indicated by dotted lines in Figure 4.

Thus it will be seen that after one of the sheets 1 has been placed with its recesses uppermost, all of the recesses can be filled with fruit after which another sheet 1 can be placed with its recesses face lowermost so that the upper portion of the fruit will project thereinto and the two sheets rest one upon the other. A sheet 5 is then positioned on the upper inverted sheet 1 so that its protuberances 7 will nest between the protuberances 2 as indicated by dotted lines in Figure 4. The protuberances on each mat will extend between but will be out of contact with the walls of the protuberances on the next adjoining mat. 95 Fruit is then placed within the recesses 6 after which an inverted sheet 5 is placed over the fruit. A sheet 1 is then placed on this upper sheet 5 in the same relative position as the lowermost sheet 1 and the operation of placing the sheets and filling them is then repeated as described until a stack of packed fruit has been built up to desired proportions.

Before the sheets 1 and 5 are used they are sprayed with a mixture of lime and sulphur which will adhere to the fibrous surfaces of the paper pulp sheets and act as a germicide to prevent rotting of the packed fruit. Obviously any other kind

of germicide can be used if suitable. Importance is attached to the fact that the bottoms of the recesses of the mats rest flat upon the sheets adjacent thereto. Thus sagging of the material under the weight of the fruit is eliminated and the fruits maintained in proper relation to each other during shipment. The recessed portions are supported solely at their bottoms where they rest between the recesses in the next tray thereunder. The bottom tray of each pair of trays bridges over the protuberances on the next tray therebelow and only touches the lower tray between the protuberances. This is shown in Fig. 3 of the drawings. Thus the sheets of a stack will be free to flex under the weight of the housed fruit and in no instance will the weight of the fruit be transmitted direct through the walls of the recesses to the fruits thereunder. Consequently bruising of the fruits is avoided.

What is claimed is:—

1. A container for fruit comprising superposed molded mats arranged in pairs, each pair having recesses in one face formed in series, the recesses of each series communicating, one mat of each pair being inverted so that the recesses in the mats of

each pair will match, there being protuberances upon each mat produced by the formation of the recesses, the protuberances on each mat resting flat on the mat of the next adjoining pair and between but out of contact with the walls of the protuberances on said adjoining pairs of mats.

2. A container for fruit comprising superposed molded mats arranged in pairs, each pair having recesses in one face formed in series, the recesses of each series communicating, one mat of each pair being inverted so that the recesses in the mats of each pair will match, there being protuberances upon each mat produced by the formation of the recesses, the protuberances on each mat resting flat on a mat of the next adjoining pair and between but out of contact with the walls of the protuberances on said mat, and a germicide carried by each of the mats.

In testimony that I claim the foregoing as my own, I have hereto affixed my signature in the presence of two witnesses.

HARRY JAY THOMPSON.
